(57) **CLAIM**

The ornamental design for a underarm thermometer, as shown and described.

DESCRIPTION

FIG. 1 is a perspective view of an underarm thermometer according to an embodiment of the present invention;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof;

FIG. 7 is a perspective view of an underarm thermometer according to an alternate embodiment of the present invention;

FIG. 8 is a front elevational view thereof;

FIG. 9 is a rear elevational view thereof;

FIG. 10 is a side elevational view thereof;

FIG. 11 is an opposite side elevational view thereof;

FIG. 12 is a top plan view thereof;

FIG. 13 is a perspective view of an underarm thermometer according to another alternate embodiment of the present invention;

FIG. 14 is a front elevational view thereof;

FIG. 15 is a rear elevational view thereof;

FIG. 16 is a side elevational view thereof;

FIG. 17 is an opposite side elevational view thereof; and,

FIG. 18 is a top plan view thereof.

The broken lines are for illustrative purposes only and form no part of the claimed design.
